UNITED STATES PATENT OFFICE.

LUCIEN A. MARSH, OF MILL VALLEY, CALIFORNIA.

GAME BOARD.

Application filed April 9, 1923. Serial No. 630,750.

To all whom it may concern:

Be it known that I, LUCIEN A. MARSH, a citizen of the United States, residing at Mill Valley, county of Marin, and State of California, have invented new and useful Improvements in Game Boards, of which the following is a specification.

This invention relates to a game board particularly adapted for use in playing the game commonly known as Mah-jongg.

It is the principal object of the present invention to provide a generally improved game board of the character referred to which is designed to expedite the playing of the game, Mah-jongg, and which is fitted with means for accommodating the playing elements of the game to prevent them from becoming injured or misplaced when the game is not in use.

In carrying out this object I provide a game board having a rectangular case in its center which is movable to permit it to form guide means around which walls of the playing pieces of the game may be built. The board is also fitted with racks, the positions of which are adjustable that they may be disposed flush with the surface of the board or in other positions supporting the playing elements constituting the players' "hands" at desired angles of inclination.

One form which the invention may assume is exemplified in the following description and illustrated by way of example in the accompanying drawings, in which:—

Fig. 1 is a plan view of the preferred form of the invention with parts broken away to clearly disclose its construction.

Fig. 2 is a perspective view of the case disclosing its construction.

Fig. 3 is a view in section through the device taken on line 3—3 of Fig. 1 showing the elements in normal position.

Fig. 4 is a similar section view with the elements in a second position.

Fig. 5 is a section through the device taken on line 5—5 of Fig. 1 showing the elements in normal position.

Fig. 6 is a similar section view showing the elements in a second position.

Fig. 7 is a perspective view of the reciprocable slide.

Figs. 8 and 9 are fragmentary views in section showing the construction and mounting of the racks.

Fig. 10 is a perspective view of one of the racks.

Referring more particularly to the accompanying drawings, 10 designates a game board of desire proportions, having a playing surface 11 and raised marginal edge 12. The latter is formed by side members 14 secured about the perimeter of the board. The side members may be of any height sufficient to maintain the board slightly elevated from its support. In this instance the side members are rabbeted along their inner surfaces to accommodate the top of a standard card table, which is fitted with legs and is of a proportion agreeing with the surface area of a board for playing Mah-jongg. It is understood that the game board itself may be fitted with rigid or folding legs if desired.

The oriental game of Mah-jongg alluded to is played with a considerable number of flat oblong playing pieces or tiles of equal dimensions. One surface of each of these tiles is marked with distinctive characters or legends, representing different factors of the game. At the beginning of the game the tiles are placed in four single rows arranged to form a perfect square. In the game this is termed building the wall. The sides of this square each comprises an equal number of the playing pieces and for the convenience of all of the players it is desirable that the square be formed as nearly as possible in the center of the table or game board so as to insure accuracy and uniformity in the setting up of the tiles and to provide each player with an equal and adequate amount of playing space between the "walls" and the edge of the board or table. It has been found difficult and tedious to arrange the playing pieces in proper position and correct numbers to form the "walls" on a plane playing surface, usually requiring considerable time which detracts from the players' interest in the game. To expedite the forming of these "walls", the center of the playing surface of the board 10 is formed with a square aperture 13 in which a vertically movable case 16 is mounted. Preferably the dimensions of each side of the case exactly agree with the overall dimension of a row of pieces built of a predetermined number.

The case 17 is formed with sides 18, a bottom 19 and a hinged cover 20, and is 110

vertically movable in the aperture so that the case 17 may be raised so that the edges of the cover will form guides along which the "walls" may be built. It should be stated that it is necessary for the surface of the board to be unbroken at times, so that the playing pieces may be shuffled about the board with their characterized faces down, which takes place previous to starting a game.

Secured beneath the playing board are two parallel guide rails 21 which serve to firmly brace the board and to guide a reciprocable slide 22. This slide is formed of rigidly connected end members 23 and side members 24; the latter are guided for movement on the rails 21. The slide is positioned directly below the case 17 and is fitted at its sides with cams 25 which cooperate with cams 26 on the filler to raise and lower the latter when the slide is reciprocated. The forward movement of the slide, which is intended to raise the case 17, is limited by the engagement of the cams 26 with the underside of the playing board. The forward movement of the slide is sufficient for the cams to raise the edges of the cover 20 above the playing surface of the board and to place the top edges of the sides 18 of the case 17 flush with the playing surface. The inward movement of the slide is limited so that the top of the case may be lowered flush with the playing surface. When the slide is in its outermost position the edges of the cover of the case 17 are a distance above the surface of the playing board forming the guides described for the accommodation of the playing pieces when building the wall. When in this position the cover 20 of the case may be raised and all the tiles on the board be placed in the case for safe keeping when the game is not in use. This is a considerable advantage as it requires but little of the player's time and prevents the tiles from becoming misplaced.

The slide may be reciprocated to raise or lower the case 17 by a rod 27 fitted with a knob 28 located at one side of the game board.

During the course of the game each player accumulates a group of tiles, which is termed the player's "hand." Each player must maintain the characters on his group of tiles concealed from the other players and must refer to them at each play to determine the course he must pursue.

The space 30 adjacent each side of the table is termed the player's playing space, where he may arrange his hand. In this space, adjacent each side of the table, the playing surface is formed with a groove 31. These grooves are of dimensions which agree with rack members 32 which are connected to the board by hinges 33. When the rack members are in normal position, as shown

in Figs. 1 and 3, the surface of the board is smooth and uninterrupted. However, when the racks are raised as shown in Figs. 4, 6, and 8, they support the tiles at a slight angle from the vertical. This angle is sufficient to permit each player to distinguish the characters on the tiles constituting his hand, but not sufficient to reveal each player's hand to the others. It is seen that when the fillers are in down position the surface of the board is smooth, permitting the tiles to be properly shuffled about the surface of the board. The racks may be yieldably held in either of three positions by spring latch members 32. When a player accumulates a winning "hand" he may lower his rack to disclose the same to the other players. In this position the rack appears as shown in Fig. 9.

In use, the device is mounted on a suitable support and playing pieces of the game are spread out over the playing surface of the board and shuffled. During this operation the top of the case 17 and the racks are maintained flush with the surface of the board. It is obvious that during the shuffling operation the raised marginal edges of the board will prevent the pieces from falling off the board and becoming lost.

When the tiles have been sufficiently shuffled, the case 17 may be raised to form guides as described, to define a square around which the tiles may be placed to build the "wall." As the guides are of a length to accommodate a required number of the tiles, it is obvious that the wall may be expeditiously formed and will contain the correct number of tiles.

During the game, the players may raise the racks to the position shown in Fig. 8 to support their "hands" on an angle to the vertical. The player accumulating a winning hand may lower the rack as described to disclose it to the other players.

It is obvious that the mounting of the racks will prevent them from becoming misplaced or broken when the table is not in use.

From the foregoing it is obvious that I have provided a comparatively simple and generally improved game board upon which walls of tiles may be easily and quickly arranged and which is fitted with a convenient storage place for the auxiliary playing elements of the game, when the latter are not in use, to prevent them from becoming misplaced and lost.

While I have shown and described the preferred form of my invention as now known to me, it is to be understood that various changes in its construction may be made without departing from the spirit of the invention as defined in the appended claims.

Having thus described my invention, what

I claim and desire to secure by Letters Patent is:—

1. A game board for playing a game employing flat oblong playing pieces, said game board having a playing surface formed with a rectangular opening at the center thereof, a rectangular hollow case having a hinged cover, said hollow case snugly fitting within said opening and vertically movable therein, the dimensions of the sides of said hollow case being such as to accommodate a predetermined number of playing pieces, said case being normally disposed with the top surface of said cover flush with the playing surface of the board, and operable means for vertically moving said case and for maintaining the top surface thereof slightly above the surface of the game board, whereby the sides of said case may serve as guiding means against which walls containing a predetermined number of playing pieces may be built.

2. A game board having a playing surface

with a rectangular opening at the center thereof, a hollow case having a hinged cover mounted in said opening and vertically movable therein, said case being normally disposed within the top surface of said cover flush with the playing surface, a reciprocal slide below the case, and co-operating means on the slide and the case adapted to vertically move the case when said slide is operated.

3. A game board having a playing surface with a rectangular opening at the center thereof, a hollow case having a hinged cover mounted in said opening and vertically movable therein, said case being normally disposed within the top surface of said cover flush with the playing surface, a reciprocal slide below the case, and co-operating cams on the slide and the case adapted to vertically move the case when said slide is operated.
